TELEPHONE ALARM CALL SYSTEM

Clarence E. Lomax, Chicago, Ill., assignor to Automatic Electric Laboratories Inc., Chicago, Ill., a corporation of Delaware

Application April 16, 1945, Serial No. 588,623
In Great Britain May 11, 1944

6 Claims. (Cl. 179—2)

1

The present invention relates to telephone alarm call systems by which is meant arrangements whereby individual subscribers can be signalled over their telephone lines at prearranged times so that the telephone bell is made to perform the functions of an alarm clock.

Arrangements have already been adopted to furnish service of this type but it has usually been performed manually as the demand has not been very great and thus it has been well within the capacity of the operating staff particularly as it was mostly required at times of comparatively light traffic. The object of the present invention is to provide arrangements whereby service of this character may be provided to a considerable number of subscribers on an automatic basis so that practically no attention is needed on the part of an operator or attendant beyond confirming that all the various subscribers concerned have acknowledged the call made to them at the appropriate time.

According to the invention, in a telephone system provided with facilities for automatically signalling certain subscribers at predetermined times a stepping switch arranged to be advanced at predetermined intervals serves to operate equipment common to a plurality of subscribers who require signalling at the corresponding time which equipment thereupon controls the application of ringing current to the lines concerned if they are not in use.

The invention will be better understood from the following description of two methods of carrying it into effect which should be taken in conjunction with the drawings accompanying the specification which are referred to as Figs. 1 and 2.

Referring first to Fig. 1, the drawing is shown separated into three portions by dotted lines and the equipment common to the whole exchange is indicated in the left-hand portion, that common to all subscribers who require signalling at a particular time in the middle portion, and that individual to one particular subscriber in the right-hand portion. The common equipment comprises essentially a rotary switch G which is arranged to be driven through one complete revolution in the 24 hours and is preferably moved step-by-step by pulses from a clock. This switch does not engage its contacts continuously but is arranged to stand for a time in a blank position between successive contacts. For instance, suppose it is decided that satisfactory service can be given by catering for times at 15 minute intervals, the switch G would be provided with 96

2

contacts and might be steadily operated by pulses at 7½ minute intervals to make 192 steps for a full revolution. In these circumstances contact would be made for 7½ minutes and then there would be a disconnection for the succeeding 7½ minutes. It will be understood that the exact mechanical details of the switch G are not of primary importance and that it might comprise a switch with a much smaller number of contacts, for instance 24, and a number of wipers, for instance eight, which were connected up in turn by a suitable arrangement of relays. Moreover, it is not essential that the period of disconnection should equal the period of connection but only that there should be an appreciable pause between successive operations.

The equipment common to the exchange also includes a cam F which is conveniently arranged to make one revolution say in one minute, and accordingly operates relay E for a short period at these intervals, whereby starting earth is connected to the various individual units of equipment as will be explained subsequently. The function of the relay E could also be taken care of by having a number of contact springs directly operated by the cam. The common equipment also includes a continuously operating double cam device K which is shown diagrammatically and may be arranged to make one revolution every three minutes. The displacement of the two constituent cams is such that the lower cam makes contact slightly before the upper cam, or in other words, that after the upper cam has closed its associated contacts, a period of practically three minutes elapses before the lower cam again closes its associated contacts. The common equipment also includes a lamp AL and a bell AB, the purpose of which will be appreciated as the description proceeds.

The equipment individual to a particular signalling time but common to all the subscribers to be signalled at that time comprises the relay D which initiates the operation and relays H and J which serve to control the alarm lamp AL and bell AB. Conveniently with this equipment are grouped the lamps L₁ to L₄ individual to the different subscribers which are signalled simultaneously at this time.

The equipment individual to each subscriber's line comprises a group of three relays A, B and C from which connection is made by way of the bracketed conductors on the extreme right to the negative, positive and private conductors of the associated line. Similar connections are

made for other subscribers' lines and other times.

Assuming now that the equipment illustrated is due to function, when switch G advances to engage the contact succeeding that shown, relay D is operated and with the timing assumed remains operated for $7\frac{1}{2}$ minutes. When relay E is next operated, which will be after a period which cannot be longer than the time taken for one revolution of the cam F, earth supplied by contacts of relay E is extended over operated contacts of relay D to the lower windings of the B relays associated with all the subscribers concerned at this time. It will be seen that the other terminals of these windings are connected to the subscribers' P conductors and consequently if any line is busy, the conductor will be earthed. Moreover if the line has been busy for longer than the operating time of relay C, this relay also will be in operated condition and will have opened a point in the initiating circuit. Relay C is made slightly slow to operate in order to enable the cutoff relay in the subscribers' line circuit to de-energize so as to prevent false operation if the line becomes idle during the period that relay E is operated. If the line is not busy, however, relay B operates in series with the cutoff relay and relay C in parallel and thereupon locks up over its upper winding dependent upon relay D, applies earth to the P conductor to busy the line thereby short-circuiting its own lower winding, disconnects relay C and connects ringing current by way of the lower winding of relay A to the line conductors. This connection of the ringing generator over the lead GEN may be direct so as to give a continuous ring, or by way of a special interrupter which will give a characteristic code to distinguish the alarm call from an ordinary telephone call. It will be appreciated that the other parties who are to be given alarm service at this particular time are dealt with in the same way. If any line is busy, a further test will be made when relay E is next operated after a further revolution of the cam F. It may well be considered, however, that the engaged condition of the line is due to a call extended thereover and accordingly that the party for whose benefit the alarm service is provided is already awake and aware of the time.

When a party being signalled replies to the alarm call by removing his receiver in the usual manner, relay A operates on the direct current loop over its lower winding in the normal manner of a ring trip relay and at its X contacts locks up dependent upon relay B. Relay A thereupon disconnects the ringing, lights the lamps L₁ individual to the subscriber and removes one of the multiple earths from the locking circuit of relays H and J. It will be seen that when the upper contact controlled by cam K is next closed after relay D operates, a circuit is completed for the lower winding of relay H which thereupon locks up by way of its upper winding; assuming the subscribers have not yet all replied, and prepares a circuit for relay J. This circuit is closed approximately three minutes later if relay H is still operated and relay J thereupon energizes and locks up to the same multiple earth if it is still available. If by this time all the subscribers concerned have replied, however, all the A relays will be operated and there will be no locking circuit for relays H and J. The operation of relay J completes a circuit for the common alarm bell AB and the lamp AL. With the timing suggested

this operation will take place between three and six minutes after the calls were initiated and since the conditions are maintained for $7\frac{1}{2}$ minutes, the attendant will have time to check over the lamps L₁ to L₄ which are still not lighted and to take what action seems desirable to investigate why no replies have been received. At the end of the $7\frac{1}{2}$ minutes period when switch G steps off its contact, relay D releases and the locked up A and B relays then also release and conditions are fully restored to normal.

Referring now to Fig. 2, this shows a slightly modified arrangement in which the general conditions remain the same and accordingly similar reference numerals have been used for corresponding pieces of equipment. The drawing is again divided by dotted lines into three parts representing respectively equipment common to the whole exchange, equipment common to all the subscribers concerned at one particular signalling time and equipment individual to a particular subscribers' line. The chief differences in the circuit arrangements are that instead of individual lamps for each subscriber a group of lamps is made to serve successively for the subscribers concerned at different signalling times, cam F and relay E have been eliminated, alarm relays H and J are made to serve in turn for each signalling time and a key M is provided as a convenient means of releasing relays H and J if one or more parties fail to respond to the alarm call. Moreover, relay B is arranged to be released on the operation of relay A so that the line is rendered free immediately after the alarm call has been answered. The general method of operation of the equipment of Fig. 2 is the same as that of Fig. 1 but it will be traced through briefly and attention called to special points of difference.

When the switch G steps to the next contact after that which it is shown engaging, earth is applied to operate relay D. This thereupon prepares circuits for the indicating lamps, prepares locking circuits for relays L, A, B, H and J, connects earth to the lower winding of the various B relays, prepares a circuit for relay H and lights the lamp LT corresponding to the particular time concerned. If the line shown is idle, relay B operates and as before connects up ringing current from the lead GEN, busies the line and disconnects relay C. If the line is busy, the operation of relay B is prevented but if it becomes idle at any time during the signalling period relay B is then enabled to operate on the release of relay C. When the party concerned responds to the alarm call, relay A operates to disconnect the ringing, to lock up over its upper winding, to release relay B by opening both its initial and locking circuits, to open a point in the circuit of the lamps and to open a multiple point in the locking circuit of relays H and J.

Assuming that all the parties concerned respond before relay H is operated by the action of cam K, all the equipment is restored to normal when the switch G steps off the contact concerned, whereupon relay D releases and brings down the various operated A relays. When the contacts operated by the upper cam K are closed, a circuit is completed for relay H which thereupon locks up by way of its upper winding; assuming that at least one party has not yet replied. If all the parties have already replied, relay H is only operated momentarily. Assuming, however, that it is able to remain operated, it prepares a circuit for relay J by way of the lower cam contacts K and

approximately three minutes after the operation of relay H, relay J is operated and locks up to the same multiple earth. Thereupon it completes a circuit for the lamps L₁—L₄ corresponding to the subscribers who have not yet replied and also completes a circuit for the alarm lamp AL and bell AB.

If the attendant desires to cut off the alarm and extinguish the lamps, he may momentarily operate the key M whereupon a circuit is completed for relay L. This relay locks up dependent upon relay D, opens the locking circuit of relay J and the initial and locking circuits of relay H so that both these relays de-energize, the alarm is cut off and the lamps are extinguished. Alternatively, if the attendant decides to allow the alarm operation to continue and all the subscribers subsequently respond, the operation of the last A relay will release relays H and J and only relay D and the various A and possibly C relays will remain operated. When the switch G steps off the contact concerned, relay D releases and brings down the A relays and also relay L if it has been operated and all the equipment is then restored to normal in readiness for controlling a similar signalling operation 15 minutes later.

The invention therefore provides a very simple arrangement whereby alarm call service may readily be provided on a large scale with the minimum of attention and by the use of a comparatively small amount of equipment.

Having now particularly described and ascertained the nature of my said invention and in what manner the same is to be performed, I declare that what I claim is:

1. In a telephone system, an exchange having a plurality of subscriber lines outgoing therefrom, time-controlled means at the exchange for automatically applying ringing current to all the idle ones of said lines for an interval at a predetermined time each day, each of said lines having, at the exchange, subscriber-controlled means for acknowledging the application of said ringing current to that line, an alarm device, a switch operating at a constant rate to measure a predetermined period during the application of the ringing current, and means effective to operate said alarm device in the event that the application of ringing current to any of said lines goes unacknowledged at the end of said predetermined period.

2. In a telephone system, an exchange having a plurality of subscriber lines outgoing therefrom, time-controlled means at the exchange for automatically applying ringing current to all the idle ones of said lines at a predetermined time each day, each of said lines having, at the exchange, subscriber-controlled means for acknowledging the application of said ringing current to that line, means normally controlled by said last means for giving an alarm at the exchange in the event that the application of ringing current to any of said lines goes unacknowledged for a predetermined period, and an alarm disabling key at the exchange manually operable to prevent said alarm from being given.

3. In a telephone system, an exchange hav-

ing a plurality of subscriber lines outgoing therefrom, time-controlled means at the exchange for automatically applying ringing current to all the idle ones of said lines at a predetermined time each day, each of said lines having, at the exchange, subscriber-controlled means for acknowledging the application of said ringing current to that line, and means so controlled by said last means in the event that the application of ringing current to any particular one of said lines goes unacknowledged for a predetermined period as to display a visual identification of said particular line.

4. In a telephone system, a group of subscriber's lines, a switch operated by a timing device, means responsive to the operation of said switch for applying ringing current to all lines of said group at a predetermined time of the day and to maintain the application of ringing current for a predetermined interval, switching devices effective if one of said lines is busy to prevent the application of ringing current to said busy one line, and said switching devices effective responsive to said one line becoming idle during said interval to apply ringing current thereto.

5. In a telephone system, groups of subscriber's lines, a set of signalling devices common to said groups, each signalling device corresponding to a line in each group, means for successively associating said devices with successive line groups and for simultaneously signalling all lines of an associated line group, a circuit prepared for each device by each said successive association, subscriber controlled means individual to each line for disabling the prepared circuit of the signalling device corresponding to such line in response to the subscriber on such line answering during said association, and means for completing the said prepared circuits of only the signalling devices which correspond to the lines failing to answer to thereby operate only the corresponding signalling devices during said association.

6. In a telephone system, a plurality of subscriber's lines, a time controlled means for automatically applying ringing current to all the idle ones of said lines at a predetermined time each day, and a relay operated responsive to a busy one of said subscriber's lines becoming idle to control the application of ringing current to said one line.

CLARENCE E. LOMAX.
